(57) CLAIM

The ornamental design for an infant bodysuit, as shown and described.

DESCRIPTION

FIG. 1 is a perspective view of an infant bodysuit.

FIG. 2 is a front view of the infant bodysuit.

FIG. 3 is a rear view of the infant bodysuit.

FIG. 4 is a lateral side view of the infant bodysuit; and,

FIG. 5 is a bottom view of the infant bodysuit.

Both lateral sides are mirror images of each other, so only one side has been illustrated (see FIG. 4). The broken lines show portions of the infant bodysuit that are not part of the claimed design.
